LONG DISTANCE TELEPHONE SIGNALING
SYSTEM

Marcel Roger Mauge, Boulogne-Billancourt, France, assignor to International Standard Electric Corporation, New York, N. Y., a corporation of Delaware

Application May 1, 1943, Serial No. 485,406
In France May 28, 1941

8 Claims. (Cl. 179—27)

1

The present invention relates to electric signaling systems specially arranged for use in long distance electrical communication circuits between central offices with which subscribers' stations are connected. More particularly, the invention provides for the transmitting and interpreting of the various signals required for the establishment of long distance telephone connections over different toll circuits.

The object of the invention is to provide long distance signaling circuits that require no modifications in the toll circuits and that can be used with incoming and outgoing circuits of any type, one-way or two-way, manual or automatic.

In long distance telephone systems, signaling is ordinarily effected by signals of frequencies comprised in the voice frequency band. In order to prevent wrong signals by speech currents, it is customary to take the following precaution: Since the circuits may contain speech currents, the control signals are interpreted or counted only if they are preceded by a preparatory signal composed of two given frequencies to the exclusion of any other. For best results, the receiving period of this preparatory signal should exceed 200 milli-seconds.

The interpretation or response to control signals may, however, be prevented by the presence of some other voice frequency current, or the signals may be mutilated by echo suppressors. In order to avoid these drawbacks, the signals transmitted after the seizure of the speech circuit, which may cause interference, are repeated until an acknowledging signal is received at the point whence these control signals were transmitted.

The present invention has among its objects the provision of means for increasing the functional dependability of voice frequency signaling in such telephone systems, and the provision of arrangements for receiving the signaling pulses.

According to one feature of the invention, means are provided for readily increasing the duration of the preparatory signal so that the signal shall be effective only after a delay exceeding 200 milli-seconds, for example, after 300, 400 or 500 milli-seconds.

According to another feature of the invention, means are provided for increasing the duration of the dialing tone if the existing code suppressors are in danger of being locked. By dialing tone is meant the tone sent by the called exchange when the equipment of that exchange is ready to receive the ringing pulses.

According to another feature of the invention,

2

a stop dial (end of dialing) signal is sent by the originating exchange and then allows the switching in of the speech circuit. The disturbances due to improper switching in of the speech circuit during ringing is thus avoided.

According to another feature of the invention, the means provided for determining the duration of the transmitted signals are also arranged to analyze the duration of the received signals. Means are provided for returning them to normal after each use.

According to another feature of the invention a release signal of a particular form is transmitted in the system at the end of each connection, in order that the circuit shall be released at the end of the reception of the release signal of the calling party for a call to a subscriber and, for a call to the operator of the distant exchange, after reception of this signal and after the operator has pulled out the plug.

According to still another feature of the invention, the trunk seizure signal is repeated so that, in the event of simultaneous seizure of both sides of the trunk, the signals may not mutilate each other. The length of the interval between repeated or maintained signals is made different for signals of opposite transmission direction, in order to avoid perpetual collision between two simultaneously transmitted signals.

According to still another feature of the invention, different seizure signals are used for the preselection of different exchanges connected in tandem.

According to another feature of the invention, the means provided for determining or verifying the duration of preparatory signals are also arranged to verify the intervals between repeated or maintained signals and to analyze the control signals. For that purpose, they are placed under the control of a relay that verifies the return to normal of these means after each use.

These and other features will be explained in detail in the following description given with reference to a specific embodiment shown in the accompanying drawings, in which:

Figs. 1 and 2, placed above one another, show a voice frequency signaling circuit incorporating features of the invention, and

Fig. 3 shows a two-way trunk circuit of a usual arrangement, with which is associated the signaling set circuit of Figs. 1 and 2. This arrangement is provided at the incoming and outgoing ends.

55

A typical code for the use of the signals is given below:

Code	Outgoing to Incoming Direction	Incoming to Outgoing Direction
<i>y</i>	Seizure (<i>r'</i>).	
<i>Y</i>	Stop dial.	
<i>x</i>	Seizure 1st direction (<i>r'</i>).	
<i>Px</i>	Pulses.	Dialing.
<i>Pz</i>	Offer or call back (<i>r</i>).	Called party's answer (<i>r</i>).
<i>PX</i>	Ringing or ring-back of operator (<i>r</i>).	Ring-back of operator (<i>r</i>).
<i>Py</i>	Calling party's release or pulling out of plug (<i>p</i>).	Called party's release (<i>p</i>).
<i>PY</i>	Acknowledgment of receipt.	Pulling out of plug (<i>p</i>).
<i>x</i> permanently.	Busy.	Acknowledgment of receipt.
		Release.
		Busy.

r' indicates that the signal is repeated until reception of the dialing tone.
r indicates that the signal is repeated until acknowledgment of the receipt.
p indicates that the signal persists, with intervals, while the cause of operation lasts.
x indicates a short pulse of frequency *x*.
y indicates a short pulse of frequency *y*.
X indicates two successive short pulses of frequency *x*.
Y indicates two successive short pulses of frequency *y*.
P indicates one long pulse of two frequencies *x* and *y*.

Terminals 1 to 7 (Fig. 1), which are grounded successively by the means determining the duration, are connected to terminals EP, RP, DS, DE, in accordance with the timing desired:

EP, duration of transmission of the preparatory signal.
 RP, minimum duration for a preparatory signal to be efficacious.
 DS, length of interval between signals for the circuit used in outgoing call.
 DE, same period for the circuit used in incoming call.

In order to facilitate an understanding of the operation, the main function of the various signaling set relays is given in the following table:

X and Rx respond to frequency *x*.
 Y and Ry respond to frequency *y*.
 G responds to all signals different from *x* and *y*.
 P, reception of a preparatory signal.
 Rp, end of reception of the preparatory signal.
 Px, reception of *x* control signal.
 Py, reception of *y* control signal.
 R1, reception of releasing signal.
 Ac, reception of the acknowledging signal.
 D disconnects the line if the preparatory signal lasts more than 100 milli-seconds.
 Cx, transmission of frequency *x*.
 Cy, transmission of frequency *y*.
 Cp, transmission of frequencies *x* and *y* (preparatory signal).
 Se neutralizes the receiving members during the transmission.
 Sx, control signal *x* instead of *y*.
 Ls, control signal composed of two pulses instead of one.
 Ia-Ib, pulse generators.
 Ta-Tb, Tx-Ty, signal-duration counters.
 Fp, end of transmission of the preparatory signal.
 Fc, end of transmission of the control signal.
 Fi, end of interval between signals and increase of the duration of the acknowledging signal.
 Si separates the successive functions of the duration-counting relay.

M, holding relay.
 En, incoming call.

The method of operation of the circuit shown in Figs. 1, 2 and 3, will now be described for given types of calls.

When the circuit is free, signaling set holding relay M is in normal position, allowing the seizure of the circuit. It is assumed that the signaling set is connected to a two-way trunk circuit which in turn is connected to the operator's positions which handles calls to the distant exchange. For calls coming from the distant exchange, the set is connected to the usual subscriber's line circuit. This signaling set could also be connected to some other circuit, for example, to a selective trunk circuit, without altering the operation.

Relay M being in normal position, the lamps LL signaling the free condition of the circuit are supplied with current over conductors 7 and 8 and one of the back contacts of relay M. Relay C is connected to the third wire of the jacks (Fig. 3).

On plugging in, relay C operates in series with the "c" wire of the cord circuit: terminal E (Fig. 3) connected to ground or battery depending upon the cord circuit used at the exchange, winding of relay C, wire 11, back contact of relay M (Fig. 2), wire 10 and wire C of the cord circuit. Relay C causes the operation of relay B: battery, winding of relay B, terminals L and M, front contact of relay C, ground on back contact of relay AP. Relay B short-circuits wires 10 and 11 so that relay C can hold after energization of relay M; it causes the operation of relay M: battery, winding of relay M (Fig. 2), back contact of relay R1, wire 12, front contact of relay B (Fig. 3), wire 13, back contact of relay Py, ground (Fig. 2). Relay M locks under the control of relay R1 in normal position. It opens the wires which normally allow seizure of the circuit.

On the other hand, relay B causes the operation of relay Ao: battery, winding of relay Ao (Fig. 3), terminals y and z, back contact of relay Sn, front contact of relay B to ground.

If the distant exchange is an automatic exchange, terminal Y will not be connected to terminal Z but to terminal o, causing over conductor 2 the operation of relay Fp (Fig. 2). Relay Fp then causes the sending of the seizure signal as follows: the energization of relay Si (Fig. 1) is effected over the circuit: battery, resistance, winding of relay Si, front contact of relay Fp, back contact of relay Fc, ground. Relay Si, in operating, causes the operation of relay Ia: battery, windings of relay Ia, back contact of relay Tb3, front contact of relay Si and ground over the energizing circuit of this relay. Relay Ia over its front contact causes on the one hand the operation of relay Ib and on the other the operation of relay Ta1: battery, winding of relay Ta1, back contact of relays Tb1 and Tb2, back contact of relay Rp, ground on front contact of relay Ia.

Relay Ib, in operating, short-circuits the energizing winding of relay Ia, which releases. Upon its release, the short circuit around relay Tb1 is removed and it operates in series with relay Ta1. On the other hand, relay Ia causes the operation of relay Cy: battery, winding of relay Cy, back contact of relay Sx, front contact of relay Fp, back contact of relay Fc and front contact of relay Ia.

Relay Tb1 in operating causes the operation of relay Fc: battery, winding of relay Fc, front contact of relay Si, front contact of relay Fp,

back contact of relay L_s , front contact of relay Tb_1 to ground. Relay F_c locks up; battery, winding and front contact of relay F_c , back contact of relay F_i , front contact of relay F_p and ground over the energizing circuit of this relay. Relay F_p opens the energizing circuit of relay S_i and hence the locking circuit of relays T_a and Tb_1 and the energizing circuit of relay I_a . Upon the release of relay I_a , the original energizing circuit of relay I_b is opened and this relay releases, allowing re-energization of relay I_a . These relays operate as beating relays creating pulses at each closing of the front contact of relay I_a . These pulses are identical with dial pulses, relay I_a being about 66 milli-seconds on its front contact and 34 milli-seconds on its back contact. This beat frequency maintained because relay I_a releases upon the closing of the short circuit around its winding by the relay I_b , and the latter is retarded in its release by a rectifier cell placed in parallel with its energizing winding.

At each operation of relay I_a , a pair of relays T_a and T_b operate as counting relays in known manner. After the energization of relay F_c , relay C_y cannot operate. Relay C_y thus operates once at the beginning of the operation, connecting a source of frequency y to the toll circuit across the back contacts of relay D and the windings of differential transformer T . Relay C_y causes the operation of slow-releasing relay S_e , which relay neutralizes the detector so that the latter may not be influenced by an echo.

After the operation of relay F_p it has been seen that the energizing circuit of relay S_i was opened, but this relay was held through its locking winding over the front contact of relay T_a . In this way, relay S_i cannot release until after the release of relay T_a .

After its release, relay I_a is pulled up by relay F_c in operating position; battery, winding of I_a , back contact of relay Tb_3 , back contact of relay S_i , back contact of relay F_i , ground to front contact of relay F_c . Relays I_a and I_b operate as before, causing at each energization the operation of one of the pairs of relays T_a and T_b .

At the end of this third pulse, relay Tb_3 operates as has been explained, causing the release of relays T_a and Tb_2 . A circuit is then closed for relay T_c ; battery, winding of relay T_c , front contact of relay Tb_3 , back contact of relay Tb_2 and ground to the front contact of relay F_c over the back contacts of S_i and F_i .

At the fourth pulse, relays T_a and Tb_1 operate again because the energizing circuit of relay I_a is not broken by the operation of relay Tb_3 , the back contact of this relay being short-circuited by a back contact of relay A_p (Fig. 3). At the end of the fifth pulse, relay T_d is operated in a manner similar to that explained for relay T_c .

Through relays T_a , T_b , T_c and T_d , a ground is placed after each pulse on terminals 1 to 7 (Fig. 1). Over terminal 1 relay F_c is energized and in the same manner, over terminal 7, the interval-end relay F_i will be energized. This relay causes the release of relay F_c and, if the cause of operation of relay F_p has not ceased as explained later, the cycle of operations recommences: sending of a y signal, then determination of the length of the interval, etc.

At the distant exchange, the y signal applied to the toll circuit is sent through differential transformer T to the detector circuit, which will

cause, after amplification and detection in a voice frequency tube circuit, the operation of relay Y , shown in the upper right-hand corner of Fig. 1. Relay R_y operates for the duration of the signal, causing, over the back contact of relay P , the energization of relays M and F_i . Relay A_p (Fig. 3) is energized in parallel with relay R_y ; battery, winding of relay A_p , back contact of relay B , back contact of relay S_n , wire 42, ground to the front contact of relay Y .

Relay M locks as explained for the outgoing circuit, preventing the seizure of the circuit through the opening of the circuits of the availability lamp AL and of relay C . At the end of the signal, relay S_i releases, allowing the operation of relays I_a and I_b pulled up over wire 4 and the ground to relay A_p (Fig. 3). The operation of these relays is intended to lengthen if need be the signal that will be sent in return should the connection to the automatic exchange occur before the echo suppressor is unlocked.

Relay A_p locks over wire 38 and a ground furnished across the back contacts of relays T_d and P . It causes the energization of relay A_t ; battery, winding of A_t , front contact of relay A_p , back contact of relay O_p , wire 33, back contact of relay P_y , front contact of relay M , wire 9, back contact of relay B , wire 13, back contact of relay P_y , ground. Relay E_n (Fig. 2) operates in parallel with the relay A_t over wire 27. It locks under the control of relay M , performing the switching required for the handling of an incoming call. Relay A_t closes a loop to the associated line circuit; terminals B_1 , B_2 , wires 41 and 40 looped in the normal position of relay R_x , resistances, self-inductance, winding of relay F_i , terminals R and Q , front contact of relay A_t , terminals A_2 and A_1 . Relay T_m is connected to the grounded wire of the line circuit. The automatic exchange is seized in a manner suited to the exchange and, when the automatic switches are in position to receive pulses, the line wire previously connected to the free ground is grounded across a winding of the supervisory relay. Relay T_m , which was short-circuited up to this moment, operates and closes over wire 6 the energizing circuit of relay C_x , which connects a source of frequency x to the toll circuit.

As has been explained before, relays T_a and T_b have been placed in operation independently of the engagement of the automatic chain and, after the operation of relay Tb_3 , the circuit of relay I_a is broken, wires 20 and 21 being no longer looped owing to the energization of relay A_p . When relay T_m operates, these wires are connected and the pulses of I_a can progress beyond the third pulse. When the fifth pulse is finished, relay T_d operates as has been seen before, opening the locking circuit of relay A_p which releases. Relay T_m releases in turn, opening the circuit of relay C_x . From the preceding description it can be seen that, regardless of the time required for the engagement of the automatic chain, the duration of the x signal will be lengthened if necessary to take into account the echo suppressor or relay S_e of the outgoing circuit.

At the originating exchange, as has been explained, a y signal is sent every 700 milli-seconds; normally the x dialing tone is received before the end of an interval, causing over wire 39 the energization of relay S_n , which opens the original energizing circuit of relay F_p . This relay in releasing stops the operation of relays I_a , I_b , T_a and T_b . At the end of the x signal, relay

F_i energized by this signal releases, giving over terminals **X** and **P** a signal to indicate to the pulse sender or to the operator the possibility of dialing over the toll circuit. The pulses act upon relay C_x through terminal **11**.

To ring a second exchange connected in transit with the first, the seizure of the trunk would be effected in a different way, for example, through a second jack causing, in addition to the energization of relay F_p , the energization of relay L_s . Two pulses of frequency y will be sent, the circuit of relay F_c being connected no longer to $Tb1$ but to $Tb2$ through relay L_s . Discrimination would be effected then at the distant exchange to put the call through in the second direction.

The dialing pulses cause the energization of relay R_x at the distant exchange. The pulses are transmitted to the automatic chain through the opening of wires **40** and **41**. At the first x pulse, relay S_n is operated over wire **39** and locks under the control of relay M .

At the end of the transmission of the digits, the outgoing circuit causes the sending of a y signal causing at the distant exchange the operation of relay F_n over wire **42**. At the originating exchange, relay F_n is operated across terminal **1** over a circuit not shown in the drawing.

Relay F_n , at the outgoing as well as at the incoming end, closes the circuit of signaling-set relay D ; battery, winding of relay D , back contacts of relays $Tb2$, $Tb3$, Tc , Px , wire **34**, front contact of relay F_n , wire **38**, back contacts of relays Td and P .

Relay D closes the talking circuit and the operator can hear the tones transmitted by the automatic exchange.

When the called party answers, the direction of the current supply is reversed and relay S_u , which was short-circuited by a rectifier cell, now operates, closing the circuit of relay S_x (Fig. 2): battery, winding of relay S_x , wire **23**, back contact of relay Cv_2 , front contact of relay S_u and ground over the locking circuit of relay A_t . Relay S_x locks: battery, winding and front contact of relay S_x , back contact of relay A_c , wire **28**, front contact of relay Cv_2 , ground. Relay Cv is energized: battery, winding of relay Cv_2 , wire **22**, front contact of relay S_x , ground on wire **21**; relay Cv_2 locks and opens the energizing circuit of relay S_x . On the other hand, relay S_x causes the energization of relay P_x : battery, winding of relay P_x , back contact of relay A_c , front contact of relay S_x , front contact of relay M to ground. Relay D releases.

The P_x signal is now transmitted as follows. Relay P_x causes the energization of relay C_p : battery, winding of relay C_p , back contacts of relays F_p and F_c , wire **5**, back contact of relay O_p , wire **36**, front contact of relay P_x , back contacts of relays R_y and R_x , ground.

Relay C_p connects the signal of composite frequencies x and y to the toll circuit and acts upon the pulse-generating relays under the control of relay S_i in normal position. As already explained, a ground is connected successively to terminals **1** to **7**. When terminal EP is connected to ground, relay F_p is operated: battery, winding of relay F_p , front contact of relay C_p , terminal EP , ground. Relay F_p locks and opens the energizing circuit of the pulse-generating relays, relays T_a and T_b releasing. The composite signal P is no longer sent. Relay F_p acts upon the pulse relays as already described through relay S_i in operating position. It should be noted that relay **75**

S_i cannot operate until after the release of relays T_a and T_b , thus ensuring the return to normal of all the relays used for determining the duration of signals.

- 5 Relays I_a , I_b , T_a , T_b operate again. Upon the first energization of relay I_a , relay C_x is operated and at the end of the first pulse, relay F_c operates as already described. Relay C_x has operated once, connecting an x signal to the toll circuit.
- 10 As already described, relays T_a and T_b are used then to insert an interval between the sending of the P_x signals, relay F_i operating at the end of the interval when terminal DE , this being an incoming call, is connected to ground. The operation continues until the arrival of the P_y acknowledging signal.

Upon arrival of this signal, the composite frequency P causes the operation of relays R_x and R_y through the detector. These two relays, in operating, close the energizing circuit of relay S_i , which will not operate until the release of relays T_a and T_b . On the other hand, relay F_i operates through relays R_x and R_y . Relay F_i causes the release of relay F_c . Relays T_a and T_b release and relay S_i operates.

The pulse-generating relays operate under the control of relays R_x and R_y which are operated.

- If a frequency different from frequencies x and y were received, relay G would be operated by the detector, opening the circuit of relay R_y . Relays T_a and T_b could not progress further.

If only frequencies x and y are received, and if the signal lasts long enough for terminal RP to be connected to ground, relay P operates to indicate the reception of a preparatory signal. At the end of the reception of this signal, relays R_x and R_y release and relay R_p operates: battery, winding of relay R_p , front contact of relay P , back contacts of relays R_p , R_y and R_x , ground.

40 Relay P is slow to release to hold until the reception of the control signal, which will cause, since this is a y signal, the energization of relay A_c : battery, winding of relay A_c , front contact of relay S_x , back contact of relay A_c , front contacts of relays R_p and R_y , back contact of relay R_x , ground. This relay causes the release of relays S_x and P_x , which stops the sending of P_x signals.

If the signal received does not cause the energization of relay R_p , for the reasons already explained, relay A_c does not operate and, at the end of the reception of the signal, relay C_p operates again after the release of relays R_x and R_y , sending the preparatory signal in the same manner as when the calling party removes the receiver. However, the duration of this signal is increased by the releasing time of relays P and F_i to take into account the echo suppressor which has been locked by the signal received, and the operation continues.

At the originating exchange, the P_x signal is received in the same manner as above described, causing the energization of relay P_x , which locks: battery, winding of relay P_x , back contact of relay A_c , front contact of relay P_x , back contact of relay F_c , wire **15**, back contact of relay A_p , wire **14**, front contact of relay M , ground. At the beginning of the reception of the preparatory signal, when relay $Tb2$ operates, relay D releases.

Relay P_x causes the energization of relay C_v which locks and changes the resistance of relay C to transmit the supervision to the operator. Depending upon the type of cord circuit used at the exchange, point SU is connected to point HR .

(high resistance during conversation) or BR (low resistance during conversation).

On the other hand, relay Px causes the energization of relay Cp, the Py signal is sent as described for the Px signal, the control signal being y instead of x, relay Sx being in normal position. At the end of the control signal, relay Fc in operating causes the release of relay Px, which stops the operation of relays Ta and Tb. Relay D operates again, closing the talking circuit.

When the called party releases, the direction of the current supply is reversed again. Relay Su releases, causing over wire 16 the energization of relay Px. The Py signal is sent to the originating exchange where relay Py is operated, its operation being ensured in the same manner as that of relay Px, which has been described before. Relay Py locks: battery, winding and front contact of relay Py, back contacts in parallel of relays Tb2 and Td, back contact of relay En, wire 28, front contact of relay C, back contact of relay Ap, ground. This provides supervision over wire 31 or 32 and brings into operation relays Iz, Ib, Ta, Tb for the purpose of causing the opening of its locking circuit if a new Py signal is not received.

Relay Fc operates at each new signal, ensuring the return to normal of relays Ta and Tb.

When the operator pulls out the plug, relay C releases, opening the locking circuit of relay Py. Relay B releases, closing the circuit of relay Px: battery, winding of relay Px, wire 16, back contacts of relays At and Op, wire 33, front contact of relay M, wire 9, back contact of relay B, wire 13, back contact of relay Py, ground.

Relay Px causes the sending of the Py signal. At the distant exchange, relay Py operates, opening the locking circuit of relay At, which releases, releasing the automatic chain.

The releasing signal is then sent from the distant exchange to the originating exchange. For this, relay Ls is operated upon the release of relay At: battery, winding of relay Ls, front contacts of relays En, Py, and M, wire 9, back contact of relay B, wire 13, front contact of relay Py, back contact of relay Fc, ground. Relay Px is operated, the sending of the preparatory signal is effected, the y control signal is sent but relay Ls being operated, relay Fc does not operate until after the energization of relay Tb2. Two y pulses are therefore sent constituting the Y control signal characteristic of the release. At the end of this control signal, relay Fc, in operating, opens the locking circuit of relay M which, in releasing, releases all the locked and closed relays, allowing new seizure of the circuit.

At the originating exchange, the preparatory signal causes, as is known, the energization of relay Rp, the control signal being composed of two pulses. Relays Ta1 and Tb1 and then Ta2 and Tb2 operate. Since the signal was not of frequency x, relay Px is in normal position. Relay R1 is operated: battery, winding of relay R1, back contact of relay Px, front contact of relay Rp, back contact of relay Si, front contact of relay Tb2, ground.

Relay R1 transfers the locking circuit of relay M to the energization circuit of relay R1. This relay locks over the front contact of relay M. At the end of the signal, when relay Rp releases, relays M and R1 release, releasing the circuit.

Thus, it will be seen that the release is not effected until the two exchanges have sent their releasing signal precluding any possibility of locking.

Furthermore, the release signal being differ-

ent from the other signals, it is easy to provide such an arrangement that the circuits used at exchanges seized in transit shall respond only to the release signal.

The calling of the operator of the distant exchange is possible up to the time the called party answers. The operator of the originating exchange momentarily depresses the ringing key of the cord circuit, causing the momentary energization of relay Ao over wires 23 and 30. Relays Sx and Ls are operated and locked, relay Px is operated and, as will be readily understood from the foregoing description, the preparatory signal followed by two pulses of frequency x is sent. This combination constitutes the signal called PX. As already explained, relay Cv1 operates over wire 35. Relay Ls connects the ringing return to the cord circuit.

At the distant exchange, relay Px operates and, since the control signal is made up of two pulses, relay Op is operated; battery, winding of relay Op, back contact of relay Cv2, wire 31, front contacts of relays Px and Rp, back contact of relay Si, front contact of relay Tb2, ground.

Relay Op is locked: battery, winding and front contact of relay Op, wire 35, back contact of relay Py, front contact of relay M, wire 9, back contact of relay B, wire 13, back contact of relay Py, ground.

Relay Op closes the circuit of the ringing lamps. One of the operators listens in by plugging in a cord circuit.

Relay C operates, its circuit being closed by one of the contacts of relay Op, which short-circuits wires 10 and 11 opened by relay N of the signaling set. Relay B operates, opening the locking circuit of relay Op. The ringing lamps are extinguished, signaling-set relay D is operated upon the energization of relay C and the conversation can take place.

To ring back the operator, the same operations are performed and, this time, relay Op is not operated but the clearing relay of the cord circuit is momentarily operated.

Upon the arrival of the PX signal, relay Px of the signaling set is operated and locked. When relay Op releases acknowledging signal Py is sent, causing at the originating exchange the release of relays Ls, Px as already described.

It has been seen that when the operator pulled out the plug signal Py was sent continuously. In the case of a connection towards a subscriber, this signal causes the release of the automatic chain. In the case of a call between two operators, this signal provides the supervision through variation of the resistance of relay C. Furthermore, at the distant exchange, the cord circuits do not generally have supervisory relays on the answering side, and the relay Op is operated momentarily at the same time as relay Py, affording supervision by the operator. The release signal is not sent until after the two operators have pulled out the plugs.

In the example shown in Fig. 3, the operator does not dial, the distant exchange being a manual exchange. In that case, relay Ao is operated as described before, causing over wires 23 and 30 the energization of relays Px and Ls. Relay Px is operated then: battery, winding of relay Px, back contact of relay Ac, front contact of relay Sx or Ls, ground to the front contact of relay M. Signal PX is sent then in known manner, and the circuit operates as already described for the ringing of the operators.

75 The incoming circuit could be connected also

11

to the toll automatic chain or to an incoming selector circuit without the operation of the signaling set being thereby modified.

While a specific embodiment of the invention has been described, it is clear that it is in no way limited but on the contrary is capable of numerous modifications and adaptations within the scope of the claims.

What is claimed is:

1. In a voice frequency signaling system, two switching points, means including trunk lines and switching means for establishing a circuit between said points, means at the first point for sending control signals preceded by preparatory signals over said circuit at a frequency comprised within the voice frequency band, means at the second point for sending an acknowledging signal over said circuit, acknowledging signal responsive means at the first point, means at the first point for repeating the preparatory signal until the last-mentioned means responds, and means at the first point for varying the duration of the preparatory signal and for rendering it effective only after the expiration of a predetermined period of time.

2. The system according to claim 1, and in which said means for varying the duration of the preparatory signal analyzes the duration of the acknowledging signals.

3. In a voice frequency signaling system, two switching points, means including trunk lines and switching means for establishing a circuit between said points, means at the first point for sending control signals preceded by preparatory signals over said circuit at a frequency comprised within the voice frequency band, means for sending dialing impulses from the first to the second point, means at the second point responsive to said pulses, a dialing tone signal sent from the second to the first point indicating readiness for said pulses, and means for varying the duration of the dialing tone signal.

4. In a voice frequency signaling system, two switching points, means including trunk lines and switching means for partially establishing a talking circuit between said points, means at one point for sending control signals preceded by preparatory signals over said circuit at a frequency comprised within the voice frequency band, means at the second point for sending an acknowledging signal over said circuit, acknowledging signal responsive means at the first point, means at the first point for sending dialing pulses, and a signal sent thereupon from the first point for completing the establishment of the talking circuit.

5. In a voice frequency signaling system, a plurality of switching points, trunk lines interconnecting said points, switching means at each

12

point for seizing a trunk line, means at each point for sending a signal to the other point upon the seizure of a trunk line, means for repeating the signal sent from a first to a second point at a certain interval, and means for repeating the signal sent from the second to the first point at a different interval.

6. The system according to claim 5, and means for varying the duration of the seizure signal depending on the point to which the seized trunk leads.

7. In a voice frequency signaling system, two exchanges, means including trunks and switching means for establishing a talking circuit between said exchanges, a plurality of numerically designated lines associated with each exchange, means at each exchange for sending control signals to the other over said circuit at a frequency comprised within the voice frequency band, means at each exchange for sending to the other an acknowledging signal over said circuit, acknowledging signal responsive means at each exchange, means at each exchange for sending impulses to the other representing the numerical designations of lines, and means at each exchange for determining the duration of the signals sent therefrom and analyzing the signals received thereat.

8. In a voice frequency signaling system, a plurality of exchanges, trunks for interconnecting said exchanges, numerically designated subscribers' lines terminating at each exchange, operators' positions at the exchanges, means at each exchange for sending control signals to the other, means at each exchange for sending acknowledging signals to the other, means at each exchange for sending impulses to the other representing the numerical designation of a line, switching means for establishing a talking circuit between subscribers at two exchanges over a trunk and for establishing a talking circuit between a subscriber at one exchange and an operator at the other exchange, means at each exchange for transmitting a release signal, means at each exchange responsive to the release signal received for releasing the talking circuit established to a called subscriber, and operator controlled means for releasing the talking circuit established to her position.

MARCEL ROGER MAUGE.
